R. V. SAGE.
DUMPING CAR DOOR SPREADER.
APPLICATION FILED JUNE 7, 1913.

his ATTORNEY.

UNITED STATES PATENT OFFICE.

RALPH V. SAGE, OF WESTMONT BOROUGH, PENNSYLVANIA.

DUMPING-CAR-DOOR SPREADER.

1,077,562.

Specification of Letters Patent.

Patented Nov. 4, 1913.

Application filed June 7, 1913. Serial No. 772,234.

To all whom it may concern:

Be it known that I, RALPH V. SAGE, a citizen of the United States, residing in the borough of Westmont, in the county of Cambria and State of Pennsylvania, have invented certain new and useful Improvements in Dumping-Car-Door Spreaders; and I do hereby declare the following to be a full, clear, and exact description of the invention, such as will enable others skilled in the art to which it appertains to make and use the same.

My invention relates to improvements in railway car construction and more especially to the door operating mechanism therefor.

The object of my invention is to provide a one-piece cast metal spreader-bar for connecting a plurality of aligned swinging doors which will have great strength and rigidity, as compared to the amount of material used in the construction of the same.

My invention is particularly adapted for use with hopper bottom cars, either of the hopper type, or hopper bottom gondola type, in which the doors extend below the center sills of the car on each side thereof, and are connected together in sets by means of a spreader-bar, the ends of which bear against, and are secured to, a door at either side of the center sills. The central portion of the bar passes under the center sills of the car and is provided with means for the attachment thereto of the door operating mechanism.

The car doors are usually provided with flanges extending around the outer edges thereof, in which case, it is preferable to arch or form the bar with an offset at this central portion, so the flanges of the doors may remain whole, and not cut away, thereby preserving their strength and stiffness.

Heretofore spreader-bars have been constructed either of a sheet of metal pressed into the required form, or of rolled bars cut into lengths with their central portions struck or bent up, so as to clear the flanged edges of the doors. These kinds of spreader-bars have not been found to be altogether satisfactory, either on account of not being sufficiently rigid and liable to become twisted, or from not having the proper attaching and bracing facilities for the door, and my invention is designed to obviate these difficulties.

I construct my spreader-bar of cast metal of substantially I-shape in cross section, the

central portion of the bar being arched or offset to pass or clear the flanges of each door and is formed of the fish-bellied type, that is, of greater depth at its center and tapering gradually toward each end. The end flanges of my I-shaped spreader-bar are preferably attached to the outer surfaces of the doors near the outer edges thereof. Integral stiffening brackets project rearwardly from the bar toward the hinged edges of the doors and are also secured thereto, the whole thus forming a rigid connection between the door and the bar, at the same time bracing the door and preventing twisting or distortion of the bar. To further stiffen the bar, I cast, integral with the bar at intermediate points, vertical ribs which extend outwardly from the central web portion thereof and which ribs also connect the top and bottom flanges together. At the central part of the bar is formed an integral thickening provided with a cylindrical opening wherein an eye bolt may be secured, to the eye of which a link of the door operating mechanism is pivoted. This construction of a spreader-bar of cast metal in accordance with my invention enables me to distribute the metal to the best possible advantages to meet the stresses to which it is subjected in use, and the bar is of ample strength and rigidity and one which can be quickly attached to the doors. The integral bracket flange connection near the inner edge of each door forms a reinforcement at what would otherwise be the weakest point of attachment, and also braces the door, while the central cylindrical opening provides an easy means of attaching the connection to the door operating mechanism.

Having thus given a general description of my invention, I will now, in order to make the same more clear, refer to the accompanying one sheet of drawings forming part of this specification, in which:

Figure 1 is a vertical longitudinal sectional elevation on an enlarged scale, taken on the line I—I of Fig. 2, through the lower hopper portion of a car showing the hinged doors in closed position, and a spreader-bar in section attached to the forward edge of each, and enough of the adjoining car structure to illustrate the application of my invention. Fig. 2 is a vertical transverse sectional elevation taken on the line II—II of Fig. 1, showing the lower portion of a car, the hoppers extending downwardly on either

side of the center, and a pair of swinging doors adapted to close the bottom thereof, and my improved spreader-bar connecting and supporting the doors. Fig. 3 is a detached top plan view of my improved spreader-bar; Fig. 4 is a side elevation thereof; and Fig. 5 is an end elevation of the same.

Referring now to the numerals on the drawings:—1 indicates the center sills of the car and 2 the plate sides thereof. Hopper sheets 3 are attached to and extend downwardly below the bottom edges of the car sides and the center sills of the car, and the doors 4 are hinged at 5 to the bottom edges of the inclined hopper sheets and form the closures for the same.

As illustrated in the drawings, two hoppers are shown, each having a pair of swinging doors, and the doors of each hopper are connected by my improved spreader-bar 6, although it will be understood that the hoppers may be differently disposed, either transversely or longitudinally of the car, without departing from the spirit of my invention. This spreader-bar 6 is substantially I-shaped in cross section throughout a greater portion of its length, but the outer flanges of the ends of the bar are tapered toward each end, as shown, in order to economize material and dispose it to best advantage.

My improved spreader-bar is of greatest depth at its center, and is there arched or offset as at 7, and gradually decreases in depth toward each end. The web and top and bottom flanges of the bar are connected together on each side of the web by vertical stiffening ribs 8 at intermediate points along the bar. At, or near, the center, the bar is formed with an integral cylindrical thickening, as at 9, with outwardly extending vertical stiffening ribs 10. A hole 11 extends through this cylindrical central portion 9 in which an eye bolt 12 is mounted.

The upper or contact surfaces 13 of the ends of the spreader-bar are straight, or in a plane, and are perforated, as shown at 14, to form the riveting surfaces for attaching it to the car doors on the outside thereof, while the outer sides of the end portions of the bar are inclined. Reinforcing brackets 15, provided with riveting surfaces, extend from one side of the bar in the same plane as the upper surfaces 13, and are similarly perforated as shown at 16. These brackets 15 extend rearwardly and are attached to the doors near the inner side edges thereof, and by this construction the door is braced both longitudinally and transversely. The hole through the central cylindrical portion of the bar affords means for attaching the eye bolt 12 to which is pivoted a link 17 of the door operating mechanism.

35 The spreader-bar is so constructed as to

enable it to be used on either set of doors by simply reversing the bar end for end, as will be clearly understood by referring to the drawings.

While I have shown and described my invention in considerable detail, I do not wish to be limited to the exact details of construction shown, but may use such substitutions, modifications or equivalents thereof, as are embraced within the scope of my invention, 70 or as pointed out in the claims.

Having thus described my invention, what I claim and desire to secure by Letters Patent, is:—

1. In a dumping car, a pair of hinged doors thereon, a cast spreader-bar substantially I-shaped in cross section, secured to, and connecting said pair of doors, the web of said I-shaped bar being provided at intervals with ribs formed integral therewith. 80

2. In a dumping car, a plurality of hinged doors thereon, a cast spreader-bar substantially I-shaped in cross section, secured to and connecting said hinged doors, said I-shaped bar being of greatest depth centrally and tapering gradually toward each end, and provided with integral ribs connecting the webs and flanges of said I-shaped bar. 90

3. In a dumping car, a plurality of hinged doors thereon, a spreader-bar substantially I-shaped in cross-section, secured to, and connecting said plurality of doors, integral ribs connecting the web and flanges of the I-shaped bar, said bar having an arched or offset central portion and tapering end portions. 95

4. In a dumping car, a plurality of hinged doors thereon, a spreader-bar substantially I-shaped in cross section, integral rib connections between the web and flanges of the I-shaped bar, said spreader-bar having an offset central portion and tapering end portions, the upper faces of said tapering end portions being flat and in a plane and connected to said doors. 100

5. In a dumping car, a plurality of alined hinged doors thereon, a spreader-bar substantially I-shaped in cross section, integral transverse ribs connecting the web and flanges of the I-shaped bar, said I-shaped bar having an offset central portion and tapering end portions, the upper faces of said tapering end portions being plane and straight, perforations in the said straight faces of the end portions and a perforated integral bracket extending laterally from said end portions, whereby said bar is connected to said doors. 110

6. In a dumping car, a plurality of alined hinged doors thereon, a spreader-bar substantially I-shaped in cross section, secured to, and connecting said hinged doors, transverse ribs connecting the web and flanges of the I-shaped bar, said bar having an off- 120

set central portion and tapering end portions, the end portions of the flanges of said I-shaped bar decreasing in width toward their extremities.

- 5 7. In a dumping car, a plurality of alined hinged doors thereon, a spreader-bar substantially I-shaped in cross section, integral flanges extending from the edges of the web of said I-shaped bar, integral transverse 10 ribs connecting the web and flanges at intervals, said bar having an offset central portion and tapering end portions, the upper faces of the tapering end portions being plane and perforated, a perforated integral 15 bracket extending laterally from each of said end portions, and means for securing the spreader-bar to said doors through the said perforations.
8. In a dumping car, a plurality of alined 20 hinged doors thereon, a spreader-bar substantially I-shaped in cross section, transverse ribs connecting the web and flanges at intervals, the central portion of the bar being provided with an integral perforated

enlargement, said bar having an offset central portion and tapering end portions, the upper faces of the tapering end portions being plane, perforations in the plane faces of the end portions, and a perforated bracket extending laterally from each of 30 said end portions, its upper face being in the same plane therewith, and means for connecting said bar to the doors through said perforations.

9. A one-piece cast spreader-bar of approximately I section, with tapering ends, flanges extending laterally in a plane from the said end portions, brackets forming extensions of said flanges, the central portion of said bar being offset and 40 provided with means for attachment to the operating mechanism.

In testimony whereof, I hereto affix my signature in the presence of two witnesses.

RALPH V. SAGE.
